atty's.

UNITED STATES PATENT OFFICE.

JOHN CUNNINGHAM, OF DRIFTON, (JEDDO P. O.,) PENNSYLVANIA.

COMBINED FENCE-POST AND GATE-HINGE.

SPECIFICATION forming part of Letters Patent No. 229,385, dated June 29, 1880.

Application filed February 24, 1880.

To all whom it may concern:

Be it known that I, JOHN CUNNINGHAM, of Drifton, (Jeddo P. O.,) in the county of Lu-
zerne and State of Pennsylvania, have in-
5 vented certain new and useful Improvements
in Combined Fence-Post and Gate-Hinge; and I do hereby declare that the following is
a full, clear, and exact description of the in-
vention, which will enable others skilled in
10 the art to which it appertains to make and use
the same, reference being had to the accom-
panying drawings, which form a part of this
specification.

Figure 1 is a perspective view, Fig. 2 is a
15 side view, Fig. 3 is a cross-section, and Fig. 4
is a perspective view, of one of the gate-hinges
used in combination with my improved fence-
post.

Corresponding parts in the several figures
20 are denoted by like letters of reference.

This invention consists in the combination,
with a fence-post having T-shaped slots, of
an adjustable gate-hinge, as will be hereinaf-
ter more fully shown and described.

25 The fence-post consists of a flat body hav-
ing wings or flanges extending in both direc-
tions at right angles to said body, so as to
form a regular cross, thus: +, as clearly repre-
sented in Fig. 3 of the drawings. The post A
30 tapers upwardly and downwardly, so as to in-
sure lightness and to enable it to be easily
driven into the ground. For the latter pur-
pose the lower end is also sharpened, as shown
at B.

35 The four flanges or sides of the post are pro-
vided with T-shaped notches b, as represented
in the drawings, to receive the fence-wires,
which are held securely in said notches by
means of suitable keys. Upon the four sides the
40 said notches are arranged at various distances
from each other, so that by turning the vari-
ous sides to the front the wires of the fence

may be differently spaced and a different num-
ber of wires used in the fence. Provision may
also be made for using boards or rails instead 45
of wire.

Where gates are to be used I provide the
post with adjustable hinges of the construc-
tion shown in Fig. 4 of the drawings. These
hinges, it will be seen, consist of a butt, C,
50 having the pintle D and a laterally-projecting
T-shaped lug or catch, D', fitting in any
one of the T-shaped notches b into which it
may be slid from the side. Upon one side
the catch D' is provided with a plate or washer,
55 E, which prevents it from slipping through
the notch. Upon the other side it has a lat-
erally-projecting bolt, F, by means of which
the device may be secured upon the fence-
post by a nut and washer. These hinges may 60
be readily adjusted in any of the notches in
the fence-post. They are simple, durable, and
convenient.

My improved fence-post is simple, cheap,
and durable. It is also so light as to be easily 65
transported from place to place.

Having thus described my invention, I claim
and desire to secure by Letters Patent of the
United States—

The combination, with a fence-post con-
structed substantially as described, and hav-
ing the T-shaped notches b b, of a hinge-butt,
C, having T-shaped lug or catch D', provided
with a plate or washer, E, and bolt F, sub-
stantially as and for the purpose herein set 70
forth.

In testimony that I claim the foregoing as
my own I have hereto affixed my signature in
presence of two witnesses.

JOHN CUNNINGHAM.

Witnesses:

STEWART MACFARLAND,
OWEN FRITZINGER.
